UNITED STATES PATENT OFFICE.

EDWIN LEHR, OF WILKINSBURG, PENNSYLVANIA, ASSIGNOR TO WESTINGHOUSE ELECTRIC AND MANUFACTURING COMPANY, A CORPORATION OF PENNSYLVANIA.

VOLTAGE-REGULATOR.

1,144,604.

Specification of Letters Patent. Patented June 29, 1915.

Application filed July 19, 1913. Serial No. 780,012.

To all whom it may concern:

Be it known that I, EDWIN LEHR, a citizen of the United States, and a resident of Wilkinsburg, in the county of Allegheny and State of Pennsylvania, have invented a new and useful Improvement in Voltage Regulators, of which the following is a specification.

My invention relates to voltage regulators and it has special reference to regulators of the step type such as are employed to control the voltage of transmission lines.

My invention has for one of its objects to provide a device of the above indicated character in the operation of which destructive sparking at the contact segments is avoided.

My invention also has for an object to provide a regulator in which is embodied an automatic mechanism for the operation of the contact arms.

Voltage regulators, as commonly constructed heretofore, comprise movable arms which operate to successively engage contact segments of different potential. When the contact arm leaves one segment, an arc follows, and an arc also precedes the engagement of the arm with the succeeding segment. The contact segments are, therefore, rendered unfit for efficient use in a comparatively short time and expensive repairs are required at frequent intervals.

I propose to provide a second or auxiliary arm which operates to make a preliminary contact with one segment before the main arm leaves the preceding contact segment. Automatic mechanism operates to change the circuit connections from one arm to the other in such manner that the arm which is making or breaking contact is not connected in circuit. The circuits are made and broken during these changes by suitable oil immersed switches, and destructive sparking between the arms and segments is thereby avoided.

The details of my invention will be described in connection with the accompanying drawings in which—

Figure 1 is a front view, partially in elevation and partially in section, of a regulator constructed in accordance with my invention, parts being broken away. Fig. 2 is an end view, partially in elevation and

partially in section, of the regulator shown in Fig. 1. Fig. 3 is a detail view of a star wheel. Fig. 4 is a detail view of a cam mechanism. Figs. 5 and 6 are views in section and in elevation, respectively, of gear mechanism. Fig. 7 is an end view of a locking mechanism. Fig. 8 is a diagrammatic view of circuits and apparatus embodying my invention.

Referring particularly to Figs. 1 and 2, the regulator comprises a suitable frame that is indicated broadly at 1. The regulator comprises a pair of units which are structurally alike, and the description will therefore be limited to one of them. A dial 2 is mounted upon and insulated from the frame 1. The front face of the dial is provided with a number of contact segments 3 which are arranged in a circle about the center of the dial and are adapted to coact with a rotatable contact arm 4. The arm 4 is mounted upon a shaft 5 which is connected to operating mechanism later described. The rear face of the dial is also provided with a corresponding number of oppositely disposed contact segments 6, each of which is electrically connected to a corresponding segment 3 upon the front face of the dial. The shaft 5 is provided with an auxiliary contact arm 7 which is insulated therefrom and which coacts with the contact segments 6. The arm 7 is provided with a contact member 8 which is in constant engagement with a slip ring 9. The arms 4 and 7 are so arranged that, when either arm is in complete engagement with its respective segment, the other arm is entirely disengaged. Both the arms 4 and 7 may, however, be partially engaged at the same time with adjacent pairs of segments or with the same pair of segments.

The regulator comprises two pairs of oil-immersed switches 10 and 11. The switches 10 control the circuit connections of the main contact arms 4 and the switches 11 control the circuit connections of the auxiliary arms 7. The switches are operated in their proper sequence by the same means, in part, that are employed to actuate the contact arms.

The mechanism for controlling the contact arms 4 and 7 and the switches 10 and 11 comprises a shaft 12, one end of which

is provided with a crank 13. The shaft 12 is provided with a star wheel 14 having a notch 15 that is normally engaged by a roller 16. The roller 16 is carried by an arm 17 that is drawn toward the wheel 14 by a spring 18.

The shaft 12 is also provided with mated bevel pinions 19 which actuate intermittent bevel gear wheels 20. The gear wheels 20 are mounted upon shafts 21 which are connected to, and insulated from, the shaft 5. Each of the pinions 19 is provided with a locking ring 22 having notches 23 which co-act with teeth 24 on the gear wheels 20. The rings 22 and the teeth 24 act as a locking means to prevent rotation of the gear wheels 20 except when the notches 23 register with the teeth 24.

The shaft 12 is further provided with cams 25 which actuate levers 26. Each of the levers 26 is connected to the movable element 31 of the respective pairs of switches through a mechanism comprising a rock shaft 27, a lever 28, a link 29 and a lever 30.

The electrical circuits are illustrated in Fig. 8. An incoming three-phase transmission line consists of conductors 32, 33 and 34. The conductor 32 is connected to each of conductors 33 and 34 through transformers 35 and 36, respectively. The transformers comprise primary windings 37 and 38 and secondary windings 39 and 40. The secondary windings are divided into sections 41, the common points of which are connected to the contact segments 3. The voltage of the outgoing line is regulated by the number of sections connected in circuit by the contact arms.

Two resistors 42 are controlled by the switches 11 and are each adapted to be placed in circuit with one of the auxiliary arms 7 when the latter carry current. The resistors 42 operate as a preventive resistance or safety device during the temporary use of the arms 7. A current transformer 43 may supply current to any suitable instrument.

It may be assumed that the arms 4 and 7 occupy the positions shown in Figs. 1 and '8. The crank handle 13 is in its vertical or "running" position, the intermittent gear wheels are in mesh, the main switch 10 is closed and the auxiliary switch 55 11 is open. Current flows through the main arms 4, while the circuits of the auxiliary arms 7 are open. The actuation of the crank handle 13 through a complete revolution produces a series of operations in the sequence stated below. The main arms 4 are moved in a clockwise direction partially off the respective contact segments and the auxiliary arms 7 are moved partially on the next segments. When the arms reach 65 these positions, the intermittent gear wheels

are out of mesh. The auxiliary switch 11 then closes the circuits of the auxiliary arms 7 through the respective resistors 42, and the main switches 10 subsequently open to break the circuit of the main arms 4.

The continued actuation of the shaft 12 again brings the gear wheels 19 and 20 into mesh, and the arms 4 are moved entirely off the segments and partially into engagement with the succeeding segments. The arms 7, at the same time, move to a central position relative to the segments and then to partial engagement. The arms 4 and 7 now engage the same pair of connected segments. The cams next effect the closing of the main switches 10 and the opening of the auxiliary switches 11, in order. The main arms 4 are then in circuit and the auxiliary arms 7 are disconnected. The gear wheels are again brought into mesh by continued rotation of the shaft 12, and the arms 4 are moved to a central position on the segments, the auxiliary arms 7 taking a position midway between the segments. The notch 15 of the star wheel 14 is again engaged by the roller 16 to retain the shaft 12 and the connected mechanism in their respective positions. The various parts are now in their normal running positions.

It will be readily understood from the above description of the construction and operation of the apparatus that the contact arms which are moving on or off the respective segments are not connected in circuit and that, consequently, there will be no tendency for arcing to take place between the several contact devices. It will also be understood that the switches and contact arms will be automatically actuated in the proper sequence to produce the above results by the simple rotation of a shaft.

When the shaft 12 is operated in the opposite direction to that above described, the sequence of operations is reversed and the voltage is correspondingly affected.

While I have described my invention in its preferred form, it is understood that such changes and modifications may be made as fall within the limits of the appended claims.

I claim as my invention:

1. The combination of a plurality of stationary contact members, and a plurality of coacting movable contact members which are fixed relatively to one another, of means for automatically controlling the electrical connections of said movable members as they are moved relatively to said stationary members.

2. The combination with a plurality of stationary contact segments, a main contact arm, and an auxiliary contact arm, of electrical circuits for said arms, and means for automatically opening and closing the cir-

- cuits of said arms when said arms are simultaneously moved relatively to said segments.
3. The combination with a plurality of stationary contact members, movable main and auxiliary contact members which are fixed relatively to one another, and electrical circuits for said members, of means for automatically controlling the circuits of said movable members in accordance with their positions relative to said stationary members.
4. The combination with a plurality of stationary contact members, movable main and auxiliary contact members which are fixed relatively to one another, and electrical circuits for said members, of means for automatically controlling the circuits of said movable members in accordance with their positions relative to said stationary members.
5. The combination with a plurality of stationary contact members, and movable main and auxiliary contact members which are fixed relatively to one another, of means including electrical connections, for opening and closing the circuits of said arms only when in engagement with said contact members.
6. The combination with a plurality of stationary contact members, and a pair of coacting movable contact members arranged to successively engage said stationary members, said movable members being so related as to simultaneously engage successive stationary members, of means for simultaneously controlling the positions and the electrical connections of said movable members.
7. The combination with a plurality of stationary spaced contact members, and a plurality of coacting movable contact members which are fixed relatively to one another, of means for automatically opening the circuits of said movable members before being disengaged from said stationary contact members and for closing said circuits after said contact members are in engagement.
8. The combination with a plurality of stationary contact segments and a pair of movable contact arms for successively engaging said segments, of electrical circuits for said segments and said arms, and means for controlling the circuits of said arms in accordance with the positions of said arms relatively to said segments.
9. In a regulator, the combination with a plurality of stationary contact members, and a plurality of movable contact members which are fixed relatively to one another for successively engaging said stationary members, of means for alternately connecting said movable members in circuit as they are moved relatively to said stationary members.
10. In a regulator, the combination with a plurality of stationary spaced contact members, a plurality of coacting movable contact members which are fixed relatively to one another, and electrical connections for said movable contact members, of switches for controlling said connections, and means for alternately actuating said contact members and operating said switches.
11. In a regulator, the combination with a plurality of stationary spaced contact members, a plurality of coacting movable contact members which are fixed relatively to one another, and electrical connections for said movable contact members, of switches for controlling said connections, and means comprising an intermittent gear mechanism for alternately operating said switches and actuating said movable contact members.

In testimony whereof, I have hereunto subscribed my name this 16th day of July 1913.

EDWIN LEHR.
